DIE GAME BOARD

Albert Stubbmann, Franklin Lakes, N.J., assignor to
Gabriel Industries, Inc., New York, N.Y.

Filed Mar. 11, 1974, Ser. No. 450,015

Term of patent 14 years

Int. Cl. D21—01

U.S. Cl. D34—5 SS

FIG. 1.

FIG. 2.

FIG. 3.

FIG. 1 is a top plan view of a die game board showing my new design. The sliding pieces are attached to the board.

FIG. 2 is a side elevational view thereof; and

FIG. 3 is a bottom plan view thereof.

I claim:

The ornamental design for a die game board, as shown and described.
